UNITED STATES PATENT OFFICE.

MAX WILNER, OF NEW YORK, N. Y., ASSIGNOR TO HENRY GLASS & CO., OF NEW YORK,
N. Y., A CORPORATION OF NEW YORK.

DESIGN FOR AN ARTICLE OF MANUFACTURE.

57,291.

Specification for Design.

Patented Mar. 8, 1921.

Application filed September 17, 1920. Serial No. 410,987. Term of patent 3½ years.

To all whom it may concern:

Be it known that I, MAX WILNER, a citizen of the United States, and resident of the city of New York, borough of Manhattan, county and State of New York, United States of America, have invented a new, original, and ornamental Design for an Article of Manufacture, of which the following is a specification, reference being had to the accompanying drawing, forming a part of the same, wherein—

The figure represents a plan view of my design as particularly adapted to a border for fabrics for children's skirts.

My design comprises a grouping of children at play, each provided with the implements of the game in which they are interested and dressed in costumes suitable to the season in which such games prevail; the said grouping being arranged upon a band or border for a child's dress or other fabric.

What I claim and desire to secure by Letters Patent, is:

The ornamental design for an article of manufacture substantially as shown.

MAX WILNER.
